UNITED STATES PATENT OFFICE

2,075,806

RETARDATION OF RANCIDITY

Albert K. Epstein and Benjamin R. Harris,
Chicago, Ill.No Drawing. Application June 3, 1935, Serial
No. 24,711

16 Claims. (Cl. 37—12)

Our invention relates to methods of and means for retarding or preventing spoilage or decomposition of materials having an oily constituent subject to oxidation. The invention concerns itself with improved products having the property of resisting decomposition caused by oxidation and of imparting resistance to spoilage caused by oxidation.

It is known that many types of materials, such as oils and fats and materials in which oils and fats are a constituent, are adversely affected by the presence of oxygen in the air, in that decomposition, presumed to be caused directly by oxidation, takes place and, in general, renders the article unfit for its intended use. This decomposition or spoilage sometimes manifests itself as rancidity, sometimes by discoloration, and sometimes by the loss or destruction of some important constituent, as, for example, the vitamin A constituent of cod liver oil.

Although considerable work has been done looking toward the development of anti-catalysts or antioxidants in oils, fats and the like normally subject to oxidation, the art has not developed sufficiently to enable one to predict what substances, or even what types of substances, will have a retarding or inhibiting effect. It is known, however, that certain substances which have some anti-oxidant effect in oils and fats normally subject to oxidation, will not function in the presence of other substances, as for example relatively heavy metals such as copper, iron and cobalt. These metals, as well as other substances, are said to "poison" the anti-catalyst or antioxidant. It has been found, also, that if in a given chemical substance which acts as an antioxidant or anticatalyst, a new chemical group or radical be introduced, or the position or character of groups present in the antioxidant molecule be changed, then the potency of the chemical substance as an antioxidant or anticatalyst is decreased or entirely destroyed.

Accordingly, the principal object of our invention is the provision of an improved class of anti-oxidants of an edible innocuous nature.

Another object is to retard or prevent the oxidation of organic substances, particularly oils and fats, and substances having oils and fats as constituents thereof.

Other objects and features of the invention are apparent from the foregoing description of problems involved and the following description of the manner in which these problems are over-
come.

We have discovered that esters of phosphoric acids produced in a suitable manner, as, for example, by esterifying organic carboxylic acid esters of polyhydroxy substances of a class comprising glycols, polyglycols and polyglycerols, with at least one free hydroxy group attached to a carbon of the polyhydroxy substance, with a derivative of phosphorus capable of producing an ester of a phosphoric acid, have a definite anti-oxidant or anticatalytic effect, particularly in oils and fats and compositions having an oily or fatty constituent. The organic carboxylic acid radical, preferably a fatty acid radical, may be of relatively low, intermediate, or relatively high molecular weight, the latter offering certain advantages in many instances. Preferably the fatty acid radical should have at least eight carbon atoms. Certain of the esters of phosphoric acids seem, in general, to be more potent than others, as will be pointed out. Simple phosphoric acid esters of glycols, polyglycols and polyglycerols may also be used. Such esters of phosphoric acids may be treated with alkaline substances to form acid or other salts, or may be left untreated, as desired.

The preferred type of phosphoric acid ester used in accordance with our invention is that wherein polyhydroxy substances, such as glycols, polyglycerols or polyglycols, esterified with a relatively high molecular weight fatty acid have at least one remaining hydroxy group esterified with a phosphoric acid. In general, reaction products comprising mixtures have certain advantages over relatively pure substances. Mixtures containing a relatively large proportion of glyceride esters may also be employed as will be explained further hereinafter.

In general, the substances described in the copending application of Harris, Serial No. 705,825, now Patent No. 2,026,785, are all suitable for use as antioxidants, as well as the reaction products described in the copending application Serial No. 14,528, filed April 3, 1935, as a continuation in part thereof and which is now Patent No. 2,025,986. While the composition of the phosphate substances employed in the present invention may vary, the substances should in themselves be relatively stable, although we have found that, in general, esters having an unsaturated fatty acid radical which in itself is subject to oxidation, can be used. The present application is directed particularly to those substances in which the polyhydroxy radical of the ester is a residue of a glycol, polyglycol or polyglycerol.

Example A

To 75 parts of washed and dried coconut oil mono-fatty acid esters of diethylene glycol are added, with stirring, 15 parts of phosphorus pentoxide, at about room temperature, or slightly above. The temperature rises to about 70° C., and the reaction mixture is held at this temperature for about 15 minutes. The product, a dark brown, moderately viscous liquid, is decanted or filtered from a residue of greater density which settles to the bottom. This reaction product may be used without further treatment, or it may be partially neutralized by the use of a suitable 10 antacid substance, such as sodium carbonate. When neutralized, the product becomes heavier in consistency, and is of a lighter color. In general, the acid, or partially neutralized product, is preferred for our purpose.

Example B

50 parts of mono-stearyl diethylene glycol prepared from commercial stearic acid and diethylene glycol by esterifying the commercial stearic acid with an excess of diethylene glycol, are dissolved in 250 parts of dry pyridine, and are added to 44 parts of phosphorus oxychloride dissolved in 250 parts of dry acetone in a cold condition. The solutions are suitably mixed and allowed to stand over night or until reaction has gone to completion. The acetone is then evaporated, the product dispersed in cold water, and then salted out employing on the average approximately 18% of salt. The salted-out product is boiled with about 150 cc. of water and then evaporated to dryness. The product so prepared may be treated further with an alkaline agent or it may be employed in the acid condition.

Example C

40 Substantially water-free glycerine is polymerized, preferably with the aid of an alkali catalyst, until it has an average molecular weight corresponding to a diglycerol. 166 parts of the polymerized product, 180 parts of oleic acid, and 105 parts of stearic acid of good commercial grade are mixed together and heated to a temperature of about 220 to 225° C. and maintained at that temperature for approximately two hours, the reaction mixture in the meantime being continuously stirred. Atmospheric oxygen is kept out of contact with the mixture, preferably by maintaining an atmosphere of an inert gas at the surface, for example, by bubbling carbon dioxide through the mixture continuously. The reaction should be allowed to continue until the acidity of the mixture is below 1%, the time, temperature and conditions described usually being suitable to produce this result. The product is then allowed to stand and any unreacted polyglycerol present is allowed to settle out.

To 450 parts of the mixed polyglycerol esters prepared as in the preceding paragraph, while at a temperature of approximately 60° C., 75 to 65 100 parts of finely divided phosphorus pentoxide are slowly added. A jacketed vessel may be employed to control temperature. The product is heated to approximately 120° C. and kept at that temperature for about twenty minutes. It is then 70 removed from the vessel and centrifuged to remove insoluble materials, consisting for the most part of more or less altered phosphorus pentoxide and adhering or loosely combined organic matter.

75 400 parts of this pretreated product are re-

turned to the jacketed vessel and at 50° C. fifty parts of finely divided phosphorus pentoxide are added slowly thereto with vigorous stirring. The reaction mixture is heated to about 70° C. and the temperature then rises to about 95° C. The product is kept at this temperature for a few minutes, the total time for the entire esterification step being about twenty-five minutes.

The product so prepared may be used as such or it may be treated with an anti-acid material such as sodium carbonate or ammonia to improve, somewhat, its keeping qualities.

The above examples illustrate generally suitable methods employable for producing the products which we utilize in our invention. It is to be understood that many modifications can be made not only in the processes but in the substances as well. For example, in producing the polyglyceride substances, the polyglycerol may have various average molecular weights by carrying out the polymerization so that the average of molecular weight will be greater or even lower than a diglycerol. In the copending application of Harris, Serial No. 754,087, filed November 21, 1934, various methods of making the polyglycerol and fatty acid esters thereof are described. Substantially any fatty acid esters of polyglycerol with at least one unesterified hydroxy group can be treated to form the ester of a phosphoric acid and the resulting reaction product can be utilized in our invention.

While we prefer to produce the polyglyceride derivatives by the use of the pretreatment step with phosphorus pentoxide, it is to be understood that we may modify the pretreatment step or omit it entirely and still produce products suitable for our invention. In general, when the pretreatment step is not employed, the amount of phosphorus pentoxide used in the esterification step and the time and temperature of treatment must be increased. After the pretreatment step, the product is very reactive to phosphorus derivatives and, as a result, the time and temperature may be decreased while still obtaining a much greater amount of combined phosphorus in the reaction product as a whole.

In place of esterifying polyglycerol with fatty acids, we may re-esterify oils and fats with the polyglycerol, in which case a mixture of mono- and diglycerides together with polyglycerides will be present and this entire mixture may be treated to form the ester. The product so produced can be used satisfactorily.

It is to be borne in mind that any derivative of phosphorus capable of forming an ester of phosphoric acid may be employed. The following may be considered illustrative of the use of pyrophosphoric acid as the esterifying agent as well as of the use of types of fatty acid derivatives other than those given illustratively above.

Example D

25 parts of the mono-acid esters of mixed coconut fatty acids and ethylene glycol are treated with 54 parts of pyro-phosphoric acid. The pyro-phosphoric acid is added when the mono-glycol esters are at an approximate temperature of 25° C. The temperature rises to about 45° C. and heat is thereafter applied to bring the reaction mixture to about 90° C. where it is maintained for approximately one-half hour.

Example E

Commercial stearic acid is esterified with an 75

excess of polyglycerols having the average molecular weight of a tetra-glycerol to produce an esterified product consisting essentially of the mono-stearyl tetra-glycerol. 73 parts of this 5 esterified product are treated with 54 parts of pyro-phosphoric acid, the mixture being made at a temperature not greater than about 90° C. and the product allowed to stand for about twenty minutes or until there is no further rise in temperature. The temperature of the mixture rises to approximately 125° C. and the reaction mixture is then allowed to cool.

The organic carboxylic acids employed in our 15 invention to esterify the polyhydroxy substances preparatory to the treatment to form the phosphoric acid esters are preferably fatty acids of relatively high molecular weight, say from C₈ up. We may employ saturated fatty acids or we may 20 employ unsaturated fatty acids which in themselves are subject to oxidation. Substantially any 25 of the fatty acids derived from the oils and fats of commerce may be employed, such as vegetable oils, for example, cotton seed oil, corn oil, castor oil, peanut oil, and the like, fish oils, such as 30 sardine oil, or animal fats such as lard. While, preferably, in accordance with the present invention, the free fatty acids prepared by suitable means from the oils or fats are preferred, we may also in many instances re-esterify the 35 oil or fat directly with a suitable polyhydroxy substance such as polyglycerol to produce a mixture of fatty acid esters having free hydroxy groups capable of being esterified to form esters of a phosphoric acid.

35 In the treatment of the reaction product consisting essentially of a phosphoric acid ester, various antiacid substances may be used. For example, the product may be treated with gaseous ammonia or alkali metal carbonates such as 40 sodium carbonate, or with the salts of fatty acids such as sodium stearate, calcium stearate, etc., or the salts of strong bases and weak organic acids, such as sodium acetate or aqueous solutions of alkali hydroxides, such as sodium hydroxide or potassium hydroxide. A suitable 45 method of treatment is to employ a solid, powdered anhydrous anti-acid substance, such as sodium carbonate, in amounts in excess of that theoretically necessary to completely neutralize 50 the product. That portion of the neutralizing agent which has not reacted is then removed by filter pressing, centrifuging or the like. The acid salts are very potent as anti-oxidants or anti-catalysts, and the ammonium salts, in general, 55 produce better results than alkali metal salts such as sodium salts.

Our products may be made in various ways, and any derivative of phosphorus may be used, capable of forming an ester of phosphoric acid. Examples 60 of such phosphorus containing substances are phosphorus pentoxide, pyrophosphoric acid, phosphorus halides, meta-phosphates such as ethyl meta-phosphate, phosphorus oxychlorides, etc.

65 In preparing simple esters of the polyhydroxy substances of the class described, the esterification procedure described above in general may be employed. For example, 6.7 parts of ethylene glycol are treated with 54 parts of pyrophosphoric acid at approximately room temperature. The 70 temperature of the reaction product rises to about 55 to 60° C., and the product is then heated to about 90° C. for about twenty minutes. When treating diethylene glycol or a polyglycerol product consisting essentially of diglycerol, amounts

suitably used are 11.4 and 19.3 parts, respectively, to 54 parts of pyrophosphoric acid. The spontaneous rise in temperature in each case is somewhat greater than in the case of the ethylene glycol, but the heating step may be about the same.

After esterification, the products are purified by filtering, decanting, or the like, to remove unreacted pyrophosphoric acid. The phosphoric acid esters may be used as such, or may, if desired, 10 be neutralized, at least in part, with a suitable anti-acid substance.

Example F

Pure, fresh cod liver oil is treated by the addition of approximately $\frac{1}{2}$ to $\frac{1}{5}\%$ of the reaction product of Example C. So treated, the cod liver oil will keep for a very much longer period of time than cod liver oil not so treated. Furthermore, the vitamin A content of the cod liver oil will remain unaffected after comparatively long periods of storage. Even if the oil is contaminated with known oxidation catalysts, such as copper, iron, nickel and other common metal contaminants, the anti-oxidants exert their action and retard oxidation. The amount of anti-oxidant substance used in any particular product may vary. Generally, amounts as low as .05% may be used with satisfaction, but considerably greater amounts may be employed in most cases with good results.

The particular phosphoric acid esters employed in accordance with our present invention are innocuous even if present in relatively high concentrations. This enables us to employ such phosphoric acid esters as oxidation inhibitors in substantially any types of organic substances which in themselves are employed as food, or which are employed as ingredients of foods. When employed in proportions of one-half percent or less and up to 10% based upon the oleaginous constituent of the product treated, remarkable and valuable properties are imparted to many types of materials, enabling them to be kept for much longer periods of time without suffering the type of deterioration usually accompanying oxidation.

Our improved antioxidants have an advantage in being, in general, readily soluble in or miscible with oily or fatty substances. Stock solutions or mixtures are, therefore, readily made up and easily handled containing a relatively large proportion of the antioxidant, for example, 30% to 40%.

Among the classes of substances which can be treated very satisfactorily in accordance with our present invention are substantially all of the oils and fats of commerce, such as cod liver oil, hali-but liver oil, sardine oil, salmon oil and other fish oils, cotton seed oil, peanut oil, sesame oil, rape-seed oil, lard, vegetable shortenings, and other animal and vegetable oils and fats. Many of these oils and fats are employed alone, while some of them are also employed in various ways in the food and other industries, as for example, in the form of emulsions in which they are in contact with moisture, which is known to cause oxidation to occur much more readily, while at other times these materials are mixed or associated with farinaceous or vegetable substances. Examples 60 of such substances are the residues of oil extraction from seeds, or animal fat renderings employed as cattle food and for other purposes, nuts which are often coated or treated with oils, besides having an oil content of their own, dried 65 70 75

5 milk powders, baked flour products of all kinds such as certain types of biscuits, crackers, and the like, which are kept for comparatively long periods of time, potato chips, and the like. Flour 10 preparations of various kinds, such as biscuit or cake flours, containing proteins as in milk powder, a shortening ingredient, etc., can be protected by the use of our antioxidant substances. In all materials of the character named, spoilage of 15 a type promoted by oxidation is definitely retarded by the use of phosphoric acid esters of the type described, and in some cases substantially complete inhibition for comparatively long periods is effected.

15 When treating such substances as dried milk powder, for example, the antioxidant initially may be dispersed in the liquid milk, and the milk then dried in a suitable manner, for example, by spray-drying. This procedure not only results 20 in an intimate dispersion of the antioxidant, but the antioxidant protects the oxidizable constituents of the milk during the drying process.

Example G

25 Fresh, pure lard is treated by the addition thereto of one-half percent. of the product of Example B. The reaction product of Example B may be used in its acid condition or in a partially neutralized condition with good results. In treating 30 the lard, it is advisable that a thorough dispersion be obtained, and this is readily done by first mixing the ester with a portion of the lard and then incorporating this mixture into the balance of the lard. The preferred method, however, is, 35 to incorporate the ester while the lard is in a melted condition, employing suitable agitation, and then spreading the treated lard out on a so-called lard roll from which it is scraped in the customary way. The lard so treated can be stored 40 for much longer periods of time and with less precautions against spoilage than lard not so treated.

Example H

45 To 60 parts of cottonseed oil, 40 parts of the ester prepared as described in Example A are added with agitation and in a suitable manner to prepare a thoroughly homogeneous mixture. This product will keep for long periods of time, the ester being of oleaginous character will not 50 readily separate out, or if there should be any slight separation, simple mixing will restore homogeneity. The product may be used as such, but preferably is adapted for treating other substances 55 having an oleaginous constituent normally subject to oxidation. This affords a suitable vehicle for the treatment of substances with relatively small amounts of an antioxidant.

What we claim as new and desire to protect by 60 Letters Patent of the United States is:

1. The method of retarding oxidation of organic materials having an oleaginous constituent normally subject to oxidation, which comprises incorporating into such materials an unneutralized 65 or partially neutralized phosphoric acid ester of a polyhydroxy substance of the class consisting of glycols, polyglycols and polyglycerols, wherein at least one hydroxy group of the polyhydroxy substance is replaced by a relatively high molecular weight aliphatic lipophile radical.

2. The method of retarding oxidation of organic materials having an oleaginous constituent normally subject to oxidation, which comprises incorporating into such materials an unneutralized 70 or partially neutralized phosphoric acid ester of

a polyhydroxy substance of the class consisting of glycols, polyglycols and polyglycerols, wherein at least one hydroxy group of the polyhydroxy substance is esterified with a relatively high molecular weight aliphatic organic carboxylic acid. 5

3. The method of retarding oxidation of organic materials having an oleaginous constituent normally subject to oxidation, which comprises incorporating into such materials an unneutralized 10 or partially neutralized phosphoric acid ester of a polyhydroxy substance of the class consisting of glycols, polyglycols and polyglycerols, wherein at least one hydroxy group of the polyhydroxy substance is replaced by a relatively high molecular weight fatty acid radical. 15

4. The method defined in claim 1, wherein the ester of the polyhydroxy substance also includes a proportion of a relatively high molecular weight glyceride which in itself has at least one hydroxy group esterifiable with a phosphoric acid. 20

5. The method of retarding the oxidation of organic materials having an oleaginous constituent normally subject to oxidation which comprises introducing into said materials a proportion of an ester in the form of a reaction product 25 of a relatively high molecular weight organic carboxylic acid ester of a polyhydroxy substance of the class consisting of glycols, polyglycols, and polyglycerols, said ester having at least one unesterified hydroxy group, and a derivative of phosphorus capable of forming an ester of a phosphoric acid, said ester being unneutralized or partially neutralized. 30

6. The method of retarding the oxidation of organic materials having an oleaginous constituent normally subject to oxidation which comprises introducing into said materials a proportion of an ester in the form of a reaction product 35 of a relatively high molecular weight organic carboxylic acid ester of a polyhydroxy substance of the class consisting of glycols, polyglycols, and polyglycerols, said ester having at least one unesterified hydroxy group, and phosphorous pentoxide, said ester being unneutralized or partially neutralized. 40

7. The method of retarding the oxidation of organic materials having an oleaginous constituent normally subject to oxidation, which comprises introducing into said materials a proportion of an unneutralized or partially neutralized ester of phosphoric acid formed by pretreating a mono-fatty acid ester of a polyhydroxy substance 45 of the class consisting of glycols, polyglycols and polyglycerols with phosphorus pentoxide, and then reacting the resulting product with a derivative of phosphorus capable of forming an ester of a phosphoric acid. 50

8. The method of retarding the oxidation of organic materials having an oleaginous constituent normally subject to oxidation, which comprises introducing into said materials a proportion of an unneutralized or partially neutralized ester of phosphoric acid formed by pretreating a mono-fatty acid ester of a polyhydroxy substance 55 of the class consisting of glycols, polyglycols and polyglycerols with phosphorus pentoxide, removing the phosphorus pentoxide material and adhering organic matter, and then reacting the resulting product with a derivative of phosphorus capable of forming an ester of a phosphoric acid. 60

9. The method of retarding oxidation of oils and fats in the presence of oxidation catalysts such as heavy metals, which comprises introducing into said materials a proportion of an unneutralized or partially neutralized phosphor- 70

75

acid ester of a polyhydroxy substance of the class consisting of glycols, polyglycols and polyglycerols, wherein at least one hydroxy group of the polyhydroxy substance is esterified with a relatively high molecular weight fatty acid.

10. A substantially dry product comprising oleaginous material normally subject to oxidation, having incorporated therein a phosphoric acid ester of a polyhydroxy substance of the class consisting of glycols, polyglycols and polyglycerols, wherein at least one hydroxy group of the polyhydroxy substance is replaced by a relatively high molecular weight aliphatic lipophile radical.

15. 11. A substantially dry product comprising oleaginous material normally subject to oxidation, having incorporated therein a phosphoric acid ester of a polyhydroxy substance of the class consisting of glycols, polyglycols and polyglycerols, wherein at least one hydroxy group of the polyhydroxy substance is replaced by a relatively high molecular weight fatty acid radical.

12. A substantially dry product comprising oleaginous material normally subject to oxidation, having incorporated therein a phosphoric acid ester of a polyhydroxy substance of the class consisting of glycols, polyglycols and polyglycerols.

13. A substantially dry product comprising oleaginous material normally subject to oxidation, having incorporated therein a phosphoric

acid ester of a polyhydroxy substance of the class consisting of glycols, polyglycols and polyglycerols, wherein at least one hydroxy group of the polyhydroxy substance is replaced by a relatively high molecular weight aliphatic lipophile radical, said phosphoric acid ester being neutralized at least in part by an anti-acid substance.

14. A substantially dry product comprising a triglyceride normally subject to oxidation having incorporated therein a proportion of a phosphoric acid ester of a polyhydroxy substance of the class consisting of glycols, polyglycols and polyglycerols.

15. A substantially dry product comprising a triglyceride normally subject to oxidation having incorporated therein a proportion of a phosphoric acid ester of a polyhydroxy substance of the class consisting of glycols, polyglycols and polyglycerols, wherein at least one hydroxy group of the polyhydroxy substance is replaced by a fatty acid radical.

16. A substantially dry product comprising oleaginous material of a character normally subject to oxidation and having incorporated therein an ester in the form of a reaction product of a derivative of phosphorus capable of forming an ester of phosphoric acid and a fatty acid ester of a polyhydroxy substance of a class consisting of glycols, polyglycols and polyglycerols.
